CLAIM

The ornamental design for a vehicle bumper with grille, as shown and described.

DESCRIPTION

FIG. 1 is a front, top, and left-side perspective view of a vehicle bumper with grille showing my new design; FIG. 2 is a front elevational view thereof;

FIG. 3 is a top plan view thereof;

FIG. 4 is a left-side elevational view thereof, the right-side elevational view (not provided) being a mirror image of the left-side view;

FIG. 5 is rear elevational view thereof; and,

FIG. 6 is a bottom plan view thereof.

The even broken lines in the drawings illustrate portions of the vehicle bumper with grille that forms no part of the claimed design. The dash-dot broken lines illustrate boundaries of the claim and also do not form part of the claimed design.
